United States Patent

Des. 238,698

Patented Feb. 3, 1976

238,698

PUZZLE

Robert H. Cook, Detroit, Mich.
(29084 Fairfax, Southfield, Mich. 48276)

Filed Apr. 8, 1974, Ser. No. 458,862

Term of patent 14 years

Int. Cl. D21—01
U.S. Cl. D34—15 M

The figure is a front perspective view of a puzzle, showing my new design. The interior line pattern represents vertical separations which cut through the height of the design.

I claim:

The ornamental design for a puzzle, substantially as shown and described.
